[57] CLAIM

The ornamental design for a therapeutic traction table, as shown and described.

DESCRIPTION

FIG. 1 is a perspective view of a therapeutic traction table showing my new design;

FIG. 2 is a front elevational view thereof, the rear elevational view being identical thereto;

FIG. 3 is a left end elevational view thereof, the right end elevational view being identical thereto; and,

FIG. 4 is a top plan view thereof, the bottom plan view being plain and unornamented.
